Primary Examiner — Susan Bennett Hattan*Assistant Examiner* — Marie D. Fast Horse(74) *Attorney, Agent, or Firm* — Stradling Yocca Carlson & Rauth(57) **CLAIM**

The ornamental design for the eyewear, as shown and described.

DESCRIPTION

FIG. 1 is an isometric view of the front of eyewear; FIG. 2 is a front view of the eyewear;

FIG. 3 is a back view of the eyewear;

FIG. 4 is a right side view of the eyewear;

FIG. 5 is a left side view of the eyewear;

FIG. 6 is a top view of the eyewear; and,

FIG. 7 is a bottom view of the eyewear.

The broken lines in the drawings represent portions of the eyewear that form no part of the claimed design.

1 Claim, 5 Drawing Sheets(56)
